UNITED STATES PATENT OFFICE.

LAWRENCE S. HOLMBOE, OF OKLAHOMA, OKLAHOMA.

PHONOGRAPH-RECORD.

1,316,894.

Specification of Letters Patent. Patented Sept. 23, 1919.

Application filed December 19, 1917. Serial No. 207,923.

To all whom it may concern:

Be it known that I, LAWRENCE S. HOLMBOE, a citizen of the United States, and a resident of Oklahoma city, in the county of 5 Oklahoma and State of Oklahoma, have invented a new and useful Improvement in Phonograph-Records, of which the following is a specification.

My invention relates to improvements in 10 phonograph records, and it consists in the constructions and arrangements herein described and claimed.

An object of my invention is to provide a 15 phonographic record having one or a plurality of slots by the use of which, the record is adapted to a record changing mechanism.

Another object of the invention is to provide a phonographic record having one or 20 a plurality of radiating slots in the center, with pin holes for receiving a pin, both slots and pin holes being employed in coöperation with a record changing mechanism.

Another object of the invention resides 25 in the formation of the sound groove on the surface of the record which includes blank portions at the beginning and the end.

Another object of the invention is to provide a phonographic record having a thickened 30 peripheral edge providing the record with a substantial concavity at the top and bottom surfaces, whereby air is pocketed to form an air cushion between two records when one falls upon the other, to lessen the 35 shock of the impact.

Other objects and advantages will appear in the following specification, reference being had to the accompanying drawing in which:

40 Figure 1 is a plan view of a phonographic record embodying the principles of my invention.

Fig. 2 is a cross section taken on the line 2—2 of Fig. 1;

45 Fig. 3 is a detail sectional view showing the action of pocketing the air between two records when one falls upon the other, and

Fig. 4 is a detail view of a portion of a record changing mechanism with which the 50 record is used.

This application is a continuation in part of my application filed March 10, 1916, Serial Number 88,375, for talking machines, in so far as the arrangement of the radially

arranged slots and pin holes in the center 55 of the record, is concerned. The record 1 has a hole 2 in the center, by which the record is centered upon the spindle and turn-table of a phonograph. The record 1 in the present instance, is made of any suitable 60 material or composition which will answer the requirement of recording sound vibrations by means of a sound groove etched or inscribed on one or both surfaces of the record.

65 The hole 2 communicates with one or more slots 3 which radiate therefrom. The slots 3 may gradually widen outwardly until they reach the circular terminal 9. Or the sides of the slots may be parallel as shown in my 70 application above referred to, until they reach a substantially rectangular recess 5 indicated in one instance in dotted lines in Fig. 1. The purpose of these slots is to accommodate certain supporting arms which 75 engage the bottom one of a pile of records, at predetermined times.

70 There are two or more of these supporting arms, and these are necessary to equally support the pile of records above. The provision of the plurality of arms makes it necessary to provide an equal number of slots so that when the arms are turned, all of the arms enter all slots at once and permit the lowermost record to fall flat. In practice, the slots of the various records are in 85 disalignment, so that when the lowermost record falls the solid portion of the next record engages the arms.

80 This arrangement of the arms for supporting the pile of records is shown in Fig. 4. This structure is a part of the record changing mechanism in my above entitled application, a portion of which is here briefly described. The arms are indicated 54 and are 90 fixed upon a shaft 53 upon which a pile of the records 1 is slipped through the central hole 2. The arms 54 have rollers 55 on the ends. These rollers engage solid portions 95 of the bottom record, and lessen the friction when the shaft 53 is rotated to partly 100 revolve the arms 54 beneath the pile of records. When the set of slots in the lowermost record reaches the arms 54, said record drops. The arms 54 are arranged spirally 105 to give the record a partial rotation during its fall. A stop pin 58 is provided, and is adapted to enter any one of a plurality of

pin holes 6 formed in the record 1. The records are thus prevented from turning, and the lowermost record is prevented from turning until it has fallen below the end 5 of the pin 58.

It should be emphasized that the phonographic record illustrated in Fig. 1, is designed altogether for the specific purpose of adapting the record to a record changing 10 mechanism. In this connection, it should be observed that the slots in the center of the record may be arranged in some other manner. It is conceivable that the record changing mechanism may be of such a construction 15 that the radial arrangement of the slots may not be of advantage. When this is the case, it is the intention to so rearrange the slots, either singly or in combination, that the record may be properly 20 adapted to the particular requirements.

In this connection, the record is susceptible to other modifications. Slots or notches 8 may be formed at intervals on the periphery of the record. In the present illustration, 25 these notches are shown of a semi-circular formation, and directly opposite the slots 3 in the record. The shape of these notches may be changed. They may be rectangular and elongated in formation, or they 30 may be square, V-shaped, or in fact any other suitable form so long as they may be identified as indentations on the edge of the record.

Lips or protuberances 9 are also formed 35 on the edge of the record. These lips are for the same purpose as are the notches 8, namely, for coöperating with a record changing mechanism. There is no particular virtue in the specific relative arrangement of 40 the lips and notches 8, as shown in Fig. 1, since they may be re-arranged, re-combined, or re-formed, to suit the particular needs of the particular record changing mechanism wherein the record is to be employed.

45 Resuming now, the description of the record. The record 1 is divided into five zones indicated *a*, *b*, *c*, *d*, and *e*, in Fig. 3. The zone "*a*" lies on the periphery of the record. The record 1 is thickened in this zone as at 50 7. The surface of the record slopes gradually through the width of the zone "*a*" and is perfectly smooth, having no sound groove. The purpose of the slope in the zone "*a*" is to guide the reproducing needle to the 55 sound groove, if placed on this sloping surface in the zone "*a*". Obviously, the provision of this sloping portion, makes accurate placing of the reproducing needle unnecessary, because the needle will naturally 60 gravitate toward the sound groove.

The thickened peripheral portion 7 has two other advantages. When one record is stacked upon the other the peripheral edges will, of course, lie upon the thickened portion 65 of the record beneath, and consequently

space the superposed records apart. The sound groove of the record beneath is thus protected from mutilation by the inadvertent sliding of the record on top. Another advantage is, that the record is reinforced at 70 the edge, thus giving the record considerably more mechanical strength than a simple plane disk would have. The thickened portion 7 with the sloping sides in the zone "*a*" has a distinct advantage in the operation of 75 the record changing mechanism wherein this record is used. When one record falls upon another, as indicated in Fig. 3, a certain amount of air is pocketed between the opposing surfaces of the records, thus forming 80 an air cushion which materially lessens the shock of the impact of the two records. Each record virtually has a concave surface which pockets the air in such a manner that when one record falls upon the other, the 85 arrival of the falling record on the one beneath, will be silent.

The second zone on the surface of the record 1 is indicated "*b*". The spiral groove on the surface of the record 1 begins in this 90 zone. The spiral groove, however, is blank, that is to say, there are no sound vibrations recorded therein. This blank groove also acts as a guide for the reproducing needle. Obviously, the needle may be placed anywhere in the zone "*b*" and will ultimately be guided to the beginning of the sound groove in the zone "*c*".

The end of the zone "*c*" in the groove of which the sound vibrations are recorded, 100 ends in the zone "*d*" in which the groove is simply a continuation of the groove of the zone "*c*," but is blank like the groove in the zone "*b*." The purpose of the blank groove in the zone "*d*" is to insure the proper operation of a swinging portion of the record changing mechanism in my above entitled application. The number of turns or length 105 of the groove in the zone "*d*" also determines the time elapsing between the playing 110 of the records.

The zone "*e*" is perfectly blank and is occupied by the radial slots 3 and the pin holes 6. This blank space is also used for the application of the usual label, stating the 115 name of the selection on the record, and other data.

The operation of the record will be clearly understood when the foregoing is taken in connection with the following description. 120 It has been briefly stated that the particular form of the record here illustrated is used in connection with the record changing mechanism of the pending application above referred to. This mechanism is such that 125 the pile of records illustrated in Fig. 4 is given a slight turn, whereupon the radial slots 3 in the lowermost record, move into alinement with the arms 54, whereupon the lowermost record drops and is given a slight 130

turn by the spiral formation of the arms 54. The radial slots 3 of the various superposed records are out of alinement with each other, so that when the record pile is partly turned, 5 only the lowermost record will fall.

Consider Fig. 3. When the falling record nearly reaches the record lying on the turn-table of the phonograph, the concave and opposing surfaces of the two records, formed 10 by the thickened peripheral edges 7, will cause a certain amount of air to be pocketed between the records, so that the one record falls silently upon the other. The presence of the slightly compressed body of air between the records, also materially lessens 15 the shock of the impact of the falling record, and thus the performance of the second function of protecting the record from breakage, is accomplished. The air pocketed between 20 the records, presses against the opposing surfaces thereof substantially as indicated by the arrows between the records.

The substance of which the record 1 is made, may be such as is usually employed, 25 or it may be of any material or composition which will serve the purpose of making a phonographic record for use in a record changing mechanism or a phonograph. However, in any event, the thickened peripheral portion 7 has the added advantage of 30 materially strengthening the record body. The presence of the thickened edge 7 lessens the likelihood of the record being broken in ordinary use. The thickened edge 7 also 35 serves to space the records apart when piled one on top of the other, thus protecting the sound groove in the zone "c" from possible mutilation. It will also be understood that when one record falls upon the other in the 40 act of changing the records, the records will engage at the thickened edges 7 and not upon

the bottom surface of one and the sound groove surface of the other.

The presence of the sloping surface of the record in the zone "a," and the blank portion 45 of the sound groove in the zone "b" make the accurate placing of the reproducing needle of the sound box unnecessary. If the needle should happen to fall on the sloping surface on the zone "a," it will naturally 50 gravitate toward the blank groove in the zone "b." Should the needle fall in the blank groove "b," it will presently be guided to the beginning of the sound groove in the zone "c," in which the sound vibrations are 55 recorded. The extent of the blank grooves in the zones "b" and "d," and the exact shape of the thickened portion with the sloping surfaces in the zone "a," are matters that are to be largely determined by actual experiment. 60

While the construction and arrangement of the phonographic record illustrated in the accompanying drawing is that of a generally preferred form, obviously modifications and 65 changes may be made without departing from the spirit of the invention or the scope of the claims.

I claim:

1. A record having a central opening and 70 slots communicating therewith.
2. A record having a central opening and a plurality of slots communicating with the opening and extending into the body of the record. 75
3. A record having a central opening with a plurality of slots radiating therefrom, and a plurality of apertures circumferentially arranged in said record beyond said grooves, and having a predetermined relation to said 80 slots.

LAWRENCE S. HOLMBOE.
